INVENTOR.

Samuel N. Fleming,

BY *H. L. Woodward*

ATTORNEY.

UNITED STATES PATENT OFFICE.

SAMUEL N. FLEMING, OF HOPKINSVILLE, KENTUCKY.

ACCESSORY FOR RADIO SIGNAL RECEIVERS.

Application filed September 2, 1927. Serial No. 317,199.

The invention has for an object to provide a novel apparatus for minimizing the effect of static, and improving the tone value of the function of radio receivers. It is an aim to provide an appliance of this character which may be connected in between the ordinary receiving circuit and the antenna for instance, in order to improve its reception.

Additional objects, advantages and features of invention reside in the construction, arrangement and combination of parts, as will be understood more fully from the following description and accompanying drawings, wherein

Figure 1 is a formal diagram showing a simple receiver with my appliance connected therein at 10,

Figure 2 is a detail of my auxiliary unit, Figure 3 is a detail longitudinal sectional view of the special receptacle and contents.

There is illustrated in Figure 1 a formal showing of a receiver 9, the parts of which are represented diagrammatically and the details of which need not be described, except to state that there is shown at 11 a conventional representation of a radio-frequency transformer to one end of the primary of which an antenna 12 is connected, with my improved accessory 10 interposed or connected in series to the leads from the antenna and one end of the primary of the transformer 11. The opposite end of the primary may be grounded or otherwise connected in accordance with approved practices.

The device 10 comprises an ornamental case 12, having binding posts 13 and 14 to which the leads from the antenna and to which the set may be connected. Within the box there is a sealed receptacle 15 which is customarily formed of non-conductive material. The receptacle may be closed by a screw cap 16 whereby a filling is held securely contained within the receptacle.

At opposite ends of the receptacle there are masses 17 of what is known as "steel wool", the two masses being spaced apart and out of mutual contact. Conductor plates 18 are interposed between the steel wool and the

top and bottom of the receptacle respectively so as to engage against the steel wool for a good electrical contact. Soldered to these plates there are lead wires 19 and 20, the former leading to the binding post 13. The receptacle contains a mixture of fine graphite and oil, mineral oil having been employed, such as medium or heavy lubricating oil, this mixture of oil and graphite completely filling the interstices of the steel wool. The wool is rammed in the receptacle and a certain amount of resilience in the mass of fibers causes it to press outwardly against the plates 18, as will be readily understood.

Also enclosed in the case 10 there is a variable condenser 21, one set of plates in which have flexible connections with the wire 20, while the other set of plates of the condenser are connected to the binding post 14. The condenser 21 may be of .0005 MF capacity, although other capacities may be found desirable for particular types of sets, or for receiving particular wave lengths. The capacity indicated is found to operate satisfactorily on the wave band of public broadcasting stations, as now operated.

The terminal 13 being connected to an antenna lead-in, and the binding post 14 being connected to the input terminal of a receiver, my appliance has been found to operate with great satisfaction in improving clarity of reception and to a certain extent modifying the effect of static. It is also claimed by persons who have used it to improve tone in musical reception. The reason for the effect thus produced by the appliance is not fully understood, but may be due in part to dampening effect which is developed by the fibers acting especially upon staccato impulses as are involved by static, without being appreciably active in similarly affecting the frequencies corresponding to the range of musical sounds and voice vibration.

In the use of the device, a certain degree of tuning may be done with the knob 24 connected to the movable plates of the condenser 21.

I claim:

95
100

1. In a device of the character described, a container formed of insulating material having a content of a mixture of an insulating fluid and a mass of extremely finely divided conductive material, a mass of wool-like metal fibers embedded in the mixture at each side connected respectively to the

antenna and the receiver, said masses being separated from each other a distance.

2. The structure of claim 1 in which the mass of wool-like fibres is of magnetic metal.

In testimony whereof I affix my signature.

SAMUEL N. FLEMING.
